US0D1073738S

(12) **United States Design Patent** (10) **Patent No.:** **US D1,073,738 S**
(45) **Date of Patent:** **** May 6, 2025**

(54) **AUTOMOTIVE INTERCOOLER**

(71) Applicant: **Resource Intl Inc.**, New Castle, DE (US)

(72) Inventor: **David Zdichowski**, Wilmington, DE (US)

(73) Assignee: **Resource Intl Inc.**, New Castle, DE (US)

(**) Term: **15 Years**

(21) Appl. No.: **29/850,458**

(22) Filed: **Aug. 19, 2022**

(51) **LOC (15) Cl.** **15-01**

(52) **U.S. Cl.**

USPC **D15/5**

(58) **Field of Classification Search**

(57) **CLAIM**

The ornamental design for an automotive intercooler as shown and described.

DESCRIPTION

FIG. 1 is a top perspective view of an automotive intercooler according to the present application;

FIG. 2 is a bottom perspective view of FIG. 1;

FIG. 3 is a front view of FIG. 1;

FIG. 4 is a rear view of FIG. 1;

FIG. 5 is a side view of FIG. 1;

FIG. 6 is a side view of FIG. 1;

FIG. 7 is a top view of FIG. 1; and,

FIG. 8 is a bottom view of FIG. 1.

The broken line showing is included for the purpose of illustrating unclaimed subject matter and forms no part of the claimed design.

The shade line showing is included for the purpose of illustrating contour and not surface ornamentation.

1 Claim, 7 Drawing Sheets
